UNITED STATES PATENT OFFICE.

WILLIAM HOWARD HUGHES, OF RUSHVILLE, ILLINOIS.

CAR-COUPING.

SPECIFICATION forming part of Letters Patent No. 341,010, dated May 4, 1886.

Application filed February 24, 1886. Serial No. 193,062. (No model.)

To all whom it may concern:

Be it known that I, WILLIAM HOWARD HUGHES, a citizen of the United States, residing at Rushville, in the county of Schuyler and 5 State of Illinois, have invented new and useful Improvements in Car-Couplings, of which the following is a specification, reference being had to the accompanying drawings.

My invention relates to car-couplings, and 10 has for its object to provide a coupling whereby the necessity of brakemen passing between moving cars for the purpose of coupling or uncoupling the same is avoided; and to this end it consists in the combination and arrangement of the several parts for service, 15 substantially as hereinafter described, and specifically pointed out in the claims.

In the drawings, Figure 1 represents an end elevation of a car provided with my improvements. Fig. 2 is a side view thereof. Fig. 3 is 20 a sectional view through the draw-head, showing the pin set for coupling. Fig. 4 is a detailed perspective view of my improved coupling-link, and Fig. 5 is a detail view.

25 Referring to the drawings, in which similar letters of reference designate similar parts, A designates the draw-head, of the usual well-known construction, and B the coupling-pin, having a shoulder or projection, b, formed 30 near its lower end, so that when the pin is in its coupled position in the draw-head A it rests on the upper surface thereof. The upper end of the pin B is provided with a rod, cord or rope, as shown at b', and this rod or cord 35 extends upwardly to the top of the car-body through guides or loops c, secured to the front end of the car in alignment with the pin-openings in the draw-head A.

D designates a trip lever or latch, which is 40 pivoted at d in the bifurcated outer end of an arm or support, E, which projects from and is secured to the forward end of the car-body. The upper end, d', of the trip lever or latch D projects laterally, and it rests or bears against 45 the body of the pin B, against which the latch-arm is held with considerable force by a spiral or other form of spring, F, that extends from the car-body to and is connected with the latch D above its pivotal point d. The spiral 50 spring is held in place on and permanently secured to the car-body by means of a plate,

f, which rests firmly against the body, and the plate and spring are secured in place by a bolt, f', that passes through the coils of the spring and plate into the car-body.

55

The lower end of the trip lever or latch D projects downward to a point below the draw-head A, and is normally held extended beyond the front face of the draw-head, so as to be in the path of movement of a forwardly-extending arm or trip, G, which is secured near one edge or formed with the draw-head of an approaching car.

60 J designates a link, which comprises the side and end bars, j j', of the ordinary form, and to 65 the side bars of this link is secured flat leaf-springs K K'. The springs K are secured to one of the side bars of the link near one end, at their upper face, and the springs K' are secured to the ends of the other side bar of the 70 link on the lower side thereof. Two of these springs at one end of the link bear against the walls of the draw-head in which the link is fitted, so that the free end of the link is prevented dropping down, and thus obviate the 75 danger of the link not entering the draw-head of the approaching car.

75 The operation of my device is as follows: Two cars being coupled together, and it being desirable to uncouple them, the pin B is 80 raised from the roof of the car-body by drawing on the rod or cord b' until its shoulder or projection b passes above and rests upon the laterally-projecting retaining-arm d' of the latch D, which will, by reason of the spring E, 85 pass below said shoulder b and thus hold the pin in an elevated position. In coupling cars the retaining-arm of the trip lever or latch holds the pin B elevated, and when the draw-heads come together the arm G will strike 90 the free end of the trip-lever or latch D and draw the arm d' away from the shoulder on the coupling-pin, which will then fall by gravity and engage the link, the coupling of the cars being thus performed automatically.

95

Modifications in detail of construction may be made in the herein-described invention without departing from the spirit or sacrificing the advantages thereof—as, for instance, the lower end of the latch D may be provided 100 with a laterally-projecting weighted arm, for the purpose of holding its upper arm, d', in

contact with the coupling-pin B, herein described.

Having thus fully described my invention, I claim—

- 5 1. In a car-coupling, and in combination with the draw-head A and coupling-pin B, having a shoulder or projection, *b*, and the guides *c*, with the trip lever or latch D, pivoted in a support or arm, E, and provided with laterally-projecting upper end, and a spring, F, for normally holding one end of the trip lever in the path of an approaching draw-head, substantially as described.
- 10 2. In a car-coupling, a latch, D, pivoted in

the bifurcated outer end of an arm, E, and 15 provided at its upper end with a laterally-projecting arm, in combination with a spring, F, connected at its opposite ends with the car-body and said latch, respectively, and the coupling-pin B, having a shoulder or projection, *b*, substantially as described. 20

In testimony that I claim the foregoing as my own I have hereto affixed my signature in presence of two witnesses.

WILLIAM HOWARD HUGHES.
